MASONRY LINE BLOCK

Louis N. Zinken, St. Cloud, Minn.

Application June 30, 1950, Serial No. 171,428

1 Claim. (Cl. 33—85)

1

This invention relates to guide line holders used in securing and stretching the guide lines used in wall construction, by masons while laying bricks, the important object of the invention being to provide means for supporting the line at the corners of a wall which is being constructed, and particularly at places wherein it is difficult to provide the proper support for the line under the usual conditions.

Another object of the invention is to provide a holder of this character which may be used effectively when the mortar or plastic material used in the laying of the bricks, is soft and has not set sufficiently to hold the usual line pegs or pins used in supporting masons' guide lines.

Still another object of the invention is to provide means whereby the line may be readily and easily tightened or stretched to insure a true guide in laying bricks.

With the foregoing and other objects in view which will appear as the description proceeds, the invention consists of certain novel details of construction and combinations of parts hereinafter more fully described and pointed out in the claim, it being understood that changes may be made in the construction and arrangement of parts without departing from the spirit of the invention as claimed.

Referring to the drawings:

Figure 1 is a perspective view illustrating a corner block or holder to which a masons' line is secured to anchor one end of the line.

Fig. 2 is a plan view thereof, a portion of the block having been broken away illustrating the manner of positioning the guide line thereto.

Fig. 3 is a bottom plan view of the line block.

Fig. 4 is a perspective view of the line block showing a guide line reel as mounted thereon for stretching and holding the line.

Fig. 5 is a plan view illustrating a modified form of block designed primarily for use in attachment to a metal door buck or frame.

Fig. 6 is a bottom plan view thereof.

Fig. 7 is a plan view of a further modified form of guide line block illustrating the manner of positioning the block against the corner of a wall.

Fig. 8 is a perspective view of the block shown in Fig. 7.

Fig. 9 is a plan view of a form of line holder specially designed for use in the construction of tile walls.

Fig. 10 is a perspective view of the holding device or clamp shown in Fig. 9 of the drawings.

Fig. 11 is a perspective view of a further modi-

fied form of guide line block designed for use in building tile walls.

Referring to the drawings in detail, the reference character 5 indicates a guide line block designed for use primarily by masons in holding the usual guide line during wall construction and laying of bricks.

As shown, the block is provided with a cut out portion 6 extending inwardly from one edge thereof, the cut out portion providing a clearance for one end of the guide line 7 to protect the guide line against wear and damage by being forced against the bricks of the wall which have been laid, by the block 5. An opening 8 is formed within this cut out portion 6 and extends through the block. The reference character 9 indicates a securing pin that extends transversely through the opening 8 and to which one end of the guide line 7 is secured by looping the line guide around the pin and passing the loose end under the main portion of the line guide to create a binding action to hold the cord or line against slipping with respect to the pin 9.

An inclined groove 10 is provided in the inner surface of the block 5, and is disposed intermediate the side edges of the block so that the guide line may rest therein and be directed towards the pin 9 in a true line to reduce wear on the line and at the same time support the guide line in such a way that the block will not direct pressure against the guide line to cause wear on the guide line by contact with the rough bricks being laid.

Extending from one end of the block 5, is the arm 11 which has a right angled portion 12 terminating in an outwardly extended eye 13 or finger piece, whereby the arm 11 may be conveniently handled in positioning the block at the corner of a wall under construction. This arm also is constructed in such a way that it will fit within the mortar space between adjacent bricks to insure against vertical movement of the block while in use.

The guide line block as described is designed for use in securing one end of a guide line to a wall. A similar block, indicated by Fig. 4 of the drawings, is provided for supporting the opposite end of the guide line, and this block is provided with a reel 13' which is secured to the outer surface of the block adjacent to one end thereof, the reel providing a support for the guide line 7 which may be wound on the reel to stretch or tighten the line. The reel 13' is provided with an operating arm 14 which may be held against movement by the pawl 15, to secure

the line taut, after it has been properly placed.

As shown by Figs. 5 and 6 of the drawings, the block which is indicated by the reference character 16, is formed with a cut out portion 17 which is of a construction to fit over one edge of a metal door buck or frame indicated by the reference character 18. A wing screw 19 passes through one end of the block 16 and has its inner end disposed within the cut out portion, for contact with the metal door buck or frame to cause the block to be clamped thereto. In the inner surface of this block, is a groove in which the guide line 1 is held, the groove being of a depth to completely house that portion of the guide line held therein and protect it against contact with the rough brick surface with which the guide line is used. In this form of the invention, the guide line is looped around the pin 20 in overlapped condition to set up a binding action and hold the line against movement with respect to the pin.

As shown by Fig. 7 of the drawings, the line holding block 21 is constructed primarily for use in the construction of tile walls and includes a body portion having right angled sections 22 and 23 adapted to fit over one corner of the tile wall under construction. Extending from one end of the member 22 is the hook 24 which is of a length to permit the hooked end 25 thereof to fit within the mortar space between adjacent tiles of the wall section, holding the block 21 against lateral movement when positioned against one corner of the tile wall.

The section 23 of this block is also formed with a circular opening 26 through which the pin 27 extends and around which one end of the guide line is wrapped to secure the guide line thereto. A groove is also formed on the inner surface of the section 23 of the block 21, in which the guide line is disposed to prevent contact of the line guide with the rough bricks or tiles when supported by the block.

Used in conjunction with the block 21, is the U-shaped clamp 28 which is of a width to exactly fit over the end of a tile, the ends 29 of the U-shaped clamp being extended outwardly and formed with slots 30 terminating in openings 31 at their inner ends, through which the guide line 1 extends. The clamp 28 is also provided

with line securing pins 32, around which the ends of the line may be secured in fastening the guide line to the clamp.

As shown by Fig. 11, the block indicated by the numeral 33, is provided with a curved portion 34 so designed that it will fit over a brick or tile of a particular construction to insure a close fit and hold the block against movement. In this block an opening 35 is provided adjacent to one end thereof, through which the line securing pin 36 extends. A groove 37 is formed in this block to receive the line and prevent wear of the line when in use.

Having thus described the invention, what is claimed is:

A guide line holding device comprising an elongated body of substantially rectangular cross section, said body having a transversely extending recess opening through one side intermediate the ends thereof, said body having an opening extending therethrough intermediate the ends thereof and communicating with the recess, said body also having a longitudinal guide line receiving groove in the side thereof having the recess, said groove communicating with the recess and extending through one end of the body, a line guiding and securing pin carried by the body and extending transversely across the opening along an axis which lies perpendicular to the longitudinal axis of the body, and means carried by the body and extending laterally from the end thereof remote from the groove for engaging a wall and holding said body against longitudinal movement under the influence of pull on a line extending through the groove and engaging the pin.

LOUIS N. ZINKEN.
